UNITED STATES PATENT OFFICE.

EDWARD G. BUDD AND JOSEPH A. WOLLÉ, OF PHILADELPHIA, PENNSYLVANIA, ASSIGNEES
TO HALE-KILBURN METAL COMPANY, OF PHILADELPHIA, PENNSYLVANIA, A CORPO-
RATION OF PENNSYLVANIA.

CUSHION.

No. 884,708.

Specification of Letters Patent.

Patented April 14, 1908.

Application filed April 24, 1906. Serial No. 313,405.

To all whom it may concern:

Be it known that we, EDWARD G. BUDD and JOSEPH A. WOLLÉ, both citizens of the United States, and both residing at Philadelphia, in the county of Philadelphia and State of Pennsylvania, have invented certain new and useful Improvements in Cushions, of which the following is a specification.

This invention concerns cushions such as are used for the seats and backs of car-seats and the object of the invention is to improve the construction of cushions of this type to the ends that a structure possessing great strength and which can be manufactured at small cost is obtained.

Our improved cushion comprises a frame which is formed of sheet-metal frame sections secured together at their ends, springs supported upon this frame and suitable covering material overlying and yieldingly sustained by these springs. Each of the sections of the frame preferably consists of two sheet-metal members having coacting flanges at the edges by which they are secured together and formed to provide an open space between them, and these members are interlocked in such a way that relative movement thereof lengthwise of the frame sections is precluded. The covering material of the seat is secured directly to this frame as by sewing or tacking it thereto, holes being provided in the frame for this purpose. In order that the upper edge of the cushion will readily yield to the pressure, the frame of the cushion does not extend up to the upper edge, but instead, a thin strip of metal is employed running around the entire upper edge of the cushion. This strip may be sustained in position by securing it to the ends of the flat springs commonly provided extending over and secured to the upper ends of the spiral springs. To further prevent relative displacement of the parts this strip may be covered with a suitable textile material and the covering of the cushion sewed thereto.

The preferred embodiment of our invention is illustrated in the accompanying drawings, in which

Figure 1 is a top view of a cushion broken away and sectioned in part, Fig. 2 is a section on line 2—2 of Fig. 1, Fig. 3 is a side

view of the cushion broken away and sectioned in part, and Fig. 4 is a perspective view of one of the members of a frame section.

55

Referring to these drawings, the parts of the cushion are supported upon a rectangular metallic frame consisting of side sections 1 and end sections 2. Each of these sections is formed of two members, the lower member 3 being provided with flanges 4 at its edges and the upper member 5 with folds 6 coacting with these flanges to secure the two parts together, the two parts being so formed intermediate their edges that an open space is provided between them, thus giving greater strength to the frame section as a whole. The two members 3 and 5 are interlocked in such a manner that movement thereof one on another lengthwise of the section is prevented; this may be readily effected by indenting the coacting flanges and folds as indicated at 7. The several frame sections may be secured together at their ends in any suitable manner; this is preferably done by providing overlapping portions at the ends as shown in Fig. 1 and collars lying within the frame sections at these points, into the ends of which the material of the overlapping portions is sunk. Extending between the side sections 1 of the frame are a plurality of channeled transverse rails or slats 8 secured at their ends, as by rivets, to the inwardly extending flange on the frame sections, and mounted upon these slats and upon the members of the frame are a plurality of spiral springs 9. Secured upon the upper ends of these springs and extending across the frame are a plurality of flat springs 10, each of which may, if desired, be covered by a strip of textile material to prevent it from cutting the overlying covering. Lying directly above the cushion frame and extending around the entire upper edge of the cushion is a strip 11 of thin flexible sheet-metal which is sustained in position by riveting it to the ends of all of the flat springs 10. This strip 11 is preferably covered with a canvas 12 or other fabric for a purpose hereinafter described.

Overlying the flat springs 10 and the edge strip 11 is a covering which may consist of a piece of heavy felt 13, a covering of coarse

fabric 14 usually termed the "first canvas" and an outer covering 15. We will now describe the means which we employ for securing the covering in position. Before assembling the parts of the frame-sections, we provide in the lower frame-members 3 a series of openings, as shown at 16, Fig. 4, preferably staggered to avoid weakening the member along this line, and also we provide a line of 10 openings 17 in the vertical flange of the frame-sections formed by the outer flange on the member 3 and the corresponding fold in the member 5. When the covering of the cushion is applied thereto, the first canvas 14 is drawn down tight on all sides of the cushion and is sewed to the vertical flange of the frame through the openings provided therein as indicated at 18. If desired, the felt interposed between the first canvas and the 15 springs may be of the same size as the first canvas and may be sewed to the frame in the same operation. When this has been done, the outer covering 15 is drawn down tight over the first canvas and its edge carried 20 under the bottom of the frame. Tacks 19 are then driven through the covering 15 and into the openings 16 in the frame to hold the covering in proper position. These tacks become wedged in the openings in the frame 25 and are held firmly, but if desired provision may be made for turning the ends of the tacks over upon the inside of the frame-section. The outer covering 15 of the cushion is often provided with a beading 20 at the top 30 edge of the cushion and in order to insure all the parts being held in proper relation, we sew this beaded edge to the first canvas 14 and felt 13 or the covering thereof as indicated at 21, and sew the felt to the covering 35 40 12 of the flexible metallic strip 11, as indicated at 22.

A seat cushion constructed in this manner is of ample strength to withstand the severe usage to which it is subjected and the edge of 45 the cushion as well as the top will yield to pressure; moreover the means described for securing the covering material to the frame permits of quickly and securely assembling the parts at small expense.

50 Having now described our invention, what we claim as new therein and desire to secure by Letters Patent is as follows:

1. A rectangular metallic frame consisting of four frame-sections secured together at 55 their ends and each consisting of a plurality of sheet-metal strips secured together at their edges and bent longitudinally to provide open space between the sides of the section and a flange running lengthwise of the 60 section, said flanges each having a series of openings therethrough, slats extending across the frame, spiral springs mounted on the frame, flat springs supported by said spiral

springs, a covering overlying said flat springs and a sewing interlaced through the covering 65 and the openings in said flanges to secure the covering to the frame, substantially as set forth.

2. In a cushion, a rectangular metallic frame having a flange at the outer edge 70 thereof substantially perpendicular to the plane of the frame and openings through said flange, springs supported on said frame, a covering overlying said springs, and a sewing interlaced through said covering and the 75 openings in the flange of said frame for holding the edges of the covering firmly thereto, substantially as set forth.

3. In a cushion, a rectangular metallic frame comprising frame-sections secured together at their ends, each of said sections consisting of two sheet-metal strips secured together at their edges by flanges on one strip and coacting folds on the other and formed to provide an open space between them intermediate their edges, one of said flanges and its coacting fold having a line of holes therein, springs secured upon said frame, a covering overlying said springs, and a sewing interlaced between said covering and said 90 openings to hold the covering in position, substantially as set forth.

4. In a cushion, a metallic frame having openings therein, spiral springs supported upon said frame, flat springs extending across 95 said frame and supported by said spiral springs, an inner covering overlying said flat springs, an outer covering overlying said inner covering, and a sewing and tacks coacting with said openings for securing the edges 100 of said coverings to said frame, one independently of the other, substantially as set forth.

5. In a cushion, a metallic frame having openings therein and slats extending across 105 the frame and secured at their ends thereto, spiral springs supported on said frame, flat springs supported on said spiral springs, an inner and an outer covering overlying said flat springs, a sewing interlaced between one 110 of said coverings and openings in said frame, and tacks coacting with openings in said frame for securing the other of said coverings to said frame, substantially as set forth.

6. In a cushion, a metallic frame having a flange on the upper side thereof substantially perpendicular to the plane of the frame and openings in said flange and in the lower side of the frame, springs supported on the upper side of said frame, a covering overlying said springs, a sewing holding the edge of said covering to said flange on the frame, a second covering overlying said covering, and tacks securing the second covering to the lower side of said frame, substantially 125 as set forth.

7. In a cushion, a metallic frame, springs supported thereon, a thin metal strip conforming to the shape of said frame mounted above the frame, a textile covering on said strip, a cover overlying said springs and said strip and secured at its edges to said frame, and a sewing securing said coverings together, substantially as set forth.

This specification signed and witnessed this 30th day of March, 1906.
